UNITED STATES PATENT OFFICE.

JOSEPH J. VALIQUETT AND CHARLES F. ROUSH, OF TOLEDO, OHIO.

SAND-TEMPERING MACHINE.

978,961.

Specification of Letters Patent. Patented Dec. 20, 1910.

Application filed June 30, 1910. Serial No. 569,654.

To all whom it may concern:

Be it known that we, JOSEPH J. VALIQUETT and CHARLES F. ROUSH, citizens of the United States, and residents of Toledo, in the county of Lucas and State of Ohio, have invented a certain new and useful Sand-Tempering Machine; and we do hereby declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to sand working machines, and has particular reference to a machine adapted for use in foundries, or other places where sand is employed as a molding medium, for mixing and acting on the sand after a molding operation to restore its temper.

The object of our invention is to provide an improved and highly efficient machine of this character which is simple, strong and durable in its construction, easy and rapid in its operation, and capable of acting on sand in an improved and efficient manner to quickly restore it to its original temper, separate small pieces of castings or other foreign matter therefrom, and deliver it to a predetermined point for subsequent use.

The invention is fully described in the following specification, and while in its broader aspect it is susceptible of numerous modifications, a preferred embodiment thereof is illustrated in the accompanying drawings, in which,

Figure 1 is a plan view thereof with a portion broken away. Fig. 2 is a side elevation thereof. Fig. 3 is a side elevation of the sand elevating wheel, griddle-box and associated parts, and Fig. 4 is a cross-section on the line $\alpha-\alpha$ in Fig. 1 with parts in full.

Referring to the drawings, 1, 1 designate the side-beams and 2, 2 the end beams of a rectangular or other suitable form of frame, 3 spindles projecting therefrom, and 4 and 5 the front and rear sets of wheels, which are mounted on such spindles and support the frame. The front spindles 3 are pivoted for horizontal swinging movements in brackets 6 carried by the frame sides and have steering arms 7 projecting from their inner ends and connected by a rod 8 for steering movements in unison, which movements may be

imparted to the rod in any suitable or well known manner.

On the rear portion of the frame is provided a platform 9 on which the engine or motor 10 is mounted. The motor shaft 11 carries a wheel 12 at one end, which wheel has a lateral annular flange at its periphery in inner and outer frictional contact with the small wheels 13 and 14, respectively, to drive the shafts 15 and 16 on which they are mounted. The shaft 15 is journaled in suitable bearings 17, carried by the frame, and has a pinion 18 thereon in mesh with a gear 19 on a shaft 20 journaled in bearings 21 of the frame. The ends of this shaft project beyond the frame sides and carry pinions 22, 22 in mesh with gears 23, 23 carried by the rear drive wheels 5.

In advance of the platform 9 and between the frame sides 1 is disposed a sand elevating wheel 24, which comprises the disk 25 at one end, the ring 26 at the opposite end, and the sand lifting blades 27, which connect and are secured at their ends to the inner side of the disk 25 at its edge and to the inner side of the ring 26, as shown. The disk 25 has its hub 25' loosely mounted on a hollow spindle 28, which projects inwardly from a standard 29 rising from the adjacent side beam 1, see Fig. 4. Carried by and at the outer sides of the disk 25 and ring 26 concentric to the axes thereof and laterally spaced therefrom are rings 30, 30, the outer peripheries of which are toothed to form sprockets for the drive-chains 31, 31 to engage. The end of the elevating wheel opposed to the disk 25 is braced for rotary movements by a set of idler rolls 32, which are peripherally grooved to receive the inner edge of the associated sprocket-ring 30 and are carried by a triangular frame 33 rising from the associated side beam 1. The blades 27 are preferably spirally arranged and transversely curved as shown to facilitate the picking up and elevating of sand from a subjacent surface.

At a predetermined height in the upward movement of the blades 27 the sand elevated thereby falls inwardly therefrom by gravity and drops upon a griddle or screen 34, which is carried by and arranged over a pan or trough 35, disposed centrally within the wheel 24, see Figs. 1, 3 and 4. The pan 35 is supported for reciprocatory movements at its inner end, or that disposed adjacent the disk 25, by a plunger 36, which is recipro-

cally mounted within the spindle 28, and has its outer end supported by the spring standards 37, which rise from the associated beam 1, and are secured at their upper ends to the 5 outer pan end. The spring standards 37 act on the pan 35 to cause the outer end of the plunger 36 to yieldingly bear against a cam-surface disk 38, which is shown as being located within the spindle 28 and has its shaft 10 carrying a sprocket-wheel 39 and journaled in the bearing standards 29 and 40. Upon a rotation of the cam-disk, which is effected as hereinafter described, it co-operates with the springs 37 to effect a vibration of the 15 pan 35, as is apparent. The bottom of the pan 35 tapers downwardly from its inner end and is substantially V-shaped in cross-section to facilitate a discharge of sand therefrom through the outlet 41 in the outer 20 end thereof and into the centrifugal fan or blower 42, which is carried by the frame side adjacent such outlet. The delivery pipe 43 of the blower may be directed to any desired point of discharge. 44 designates a hood 25 which is carried by the pan 35 and extends over the inner hub end of the wheel-disk 25. The tailings from the screened sand pass from the outer end of the screen 34 through outlets 45, and drop to the ground or other 30 surface over which the machine is operating, or may be caught if desired. A V-shaped part 46 at the outer end of the screen serves to direct the tailings to such outlets.

The rotary parts of the fan or blower 42 35 are driven from the shaft 16 through the medium of the train of gears 47.

48 designates a sand cutting and mixing drum, which is mounted between the frame sides 1 in advance of the elevating wheel 40 24 and has its lower peripheral edge in a plane with the lower edge of such wheel, as shown. This drum has a plurality of blades 49 disposed around the periphery thereof and arranged in successive rows extending 45 longitudinally thereof, with the blades of alternate rows oppositely inclined relative to planes transversely intersecting the drum, as shown. The arranging of the blades 49 in this manner causes them to strike the sand 50 acted on with a slanting blow, and also causes the blades of the successive rows to throw the sand in opposite directions longitudinally of the drum, due to the oppositely inclining of the blades of such rows, thus 55 effecting a thorough mixing and working of the sand to restore its temper.

The mechanism for driving the wheel 24 and drum 48 is shown in the present instance as consisting of the sprocket chain 50, which 60 communicates power from a sprocket 51 on the motor-shaft 11 to a sprocket 52, the shaft 53 of which is journaled in a bearing 54 at the forward end of the associated frame side 65 1 and carries a gear 55 on its inner end. The gear 55 meshes with a gear 56 on a shaft 57,

which is journaled in the frame transversely thereof, and carries a pair of sprocket-wheels 58 for the chains 31 which drive the sprockets 30 on the wheel 24. The drum 48 is driven by one of the chains 31 passing 70 over a sprocket wheel 59 carried at one end thereof, see Fig. 2. The mechanism just described is adapted to drive the drum 48 and wheel 24 in opposite directions, as indicated by the arrows, Fig. 2, the drum revolving in a direction to catch and pick up the sand thrown thereto. The sprocket 39 on the shaft with the cam-disk 38 is driven by the chain 50, which passes thereover, see Figs. 1 and 4. 75

In the operation of our machine, it is run over the surface on which the sand to be acted on is disposed, the sand being first moistened to the desired extent. As the drum 48 passes thereover the sand is cut up 80 and thrown back and forth by the blades 49 to effect a thorough mixing and working of the same to restore its temper and is then thrown by such blades back toward the elevating wheel 24. The revolving of this 85 wheel causes the blades 27 to scoop the sand from the floor or other surface over which it is operating and elevate it to a point where it will fall by gravity from the inner edges of the blades and drop upon the griddle or 90 screen 34. The vibratory movement of the screen, due to the action of the rapidly rotating cam-disk 38 upon the plunger 36, causes the sand to pass through the screen into the pan 35 and the tailings to work 95 through the discharge outlet 45. The sand which enters the pan 35 is directed through the outlet opening 41 into the blower 42 by which it is directed through the delivery pipe 43 to any desired point. 100

105 It is apparent that our machine provides a simple and efficient means for tempering sand, cleaning it of small casting parts or other foreign matter and delivering it to a desired point for subsequent use.

110 We wish it understood that our invention is not limited to any specific construction or arrangement of the parts except in so far as such limitations are specified in the claims.

Having thus described our invention what 115 we claim as new and desire to secure by Letters Patent, is,—

1. In a machine of the class described, a sand mixing member, a rotatable sand elevating member, means within said elevating member for screening sand, and means associated with said screening means for delivering the screened sand to a predetermined point. 120

2. In a machine of the class described, the 125 combination of a set of rotatable members arranged in tandem and rotatable in opposite directions, one member serving to mix sand over which it passes and the other serving to elevate the mixed sand, a griddle asso-

- ciated with said elevated member for screening the sand elevated thereby, and means for directing and conveying the screened sand to a predetermined point.
5. 3. In an apparatus of the class described, the combination of a frame, supporting wheels for such frame, a sand cutting and mixing drum and a sand elevating member rotatably carried by said frame one in advance of the other, means for rotating said drum and member, and means associated with the elevating wheel for cleaning the sand elevated thereby.
10. 4. In an apparatus of the class described, the combination of a wheel frame, sand mixing means and sand elevating means carried by such frame, sand screening and conveying means associated with said elevating means and mechanism for operating said several means.
15. 5. In an apparatus of the class described, the combination of a wheeled frame, a sand mixing drum carried by said frame, a rotary sand elevating member carried by said frame and adapted to discharge sand within the member at a predetermined point in its elevation, sand screening means disposed within the member, means for conveying the screened sand to a predetermined point, and mechanism for operating the drum member and conveying means.
20. 6. In an apparatus of the class described, a frame, sand mixing means carried by said frame, a hollow sand elevating wheel carried by the frame and having parts adapted to elevate sand to a predetermined height and then to permit it to drop within the wheel, a griddle for catching and screening the sand as it drops within the wheel, means associated with the griddle for conveying the screened sand to a predetermined point.
25. 7. In an apparatus of the class described, the combination of a frame, sand mixing means carried thereby, a hollow sand elevating wheel carried by the frame and having blades for picking up and elevating sand to a predetermined height and then to per-
- mit its discharge by gravity within the wheel, a griddle for catching and screening the sand within the wheel, means for vibrating the griddle, means for conveying the screened sand to a predetermined point, and mechanism for operating the sand mixing means and the wheel.
30. 8. In an apparatus of the class described, the combination of a frame, a rotary drum carried thereby and having peripheral blades arranged to effect a mixing of matter, a sand elevating member rotatably carried by said frame adjacent said drum and adapted to permit the elevated matter to drop therein at a predetermined point in its elevation, vibratory screening means for catching the matter dropped from said member, means for delivering the screened sand to a predetermined point, and mechanism for operating such mixer, elevating member and vibratory means.
35. 9. In an apparatus of the class described, a sand mixing member comprising a drum, and rows of blades arranged around such drum and inclined relative to the plane of rotation thereof, alternate rows of such blades inclining in opposite directions.
40. 10. In a machine of the class described, a movable frame, a rotary sand mixing drum and a sand elevating wheel mounted in said frame one in advance of the other and rotatable upwardly toward each other, the drum having inclined peripheral blades and the wheel being hollow and having peripherally disposed sand lifting blades, means within the wheel for screening the elevated sand and conveying it to a predetermined point, and mechanism for operating said drum.

In testimony whereof, we have hereunto signed our names to this specification in the presence of two subscribing witnesses.
